UNITED STATES PATENT OFFICE

143,376

DESIGN FOR A COMBINATION RADIO AND PHONOGRAPH TABLE

Herbert L. Weisburgh, New Rochelle, N. Y.

Application July 19, 1945, Serial No. 120,812

Term of patent 7 years

(Cl. D56—4)

To all whom it may concern:

Be it known that I, Herbert L. Weisburgh, a citizen of the United States of America and resident of the city of New Rochelle, county of Westchester, and State of New York, have invented a new, original, and ornamental Design for a Combination Radio and Phonograph Table, of which the following is a specification, reference being had to the accompanying drawing, forming a part thereof, in which

Fig. 1 is a front perspective view of a combination radio and phonograph table embodying my design, showing the record playing unit in ex-

tended position, the doors of the radio unit open, and the louvres of the speaker unit in open position, and

Fig. 2 is a side perspective view of the radio-phonograph table shown in Fig. 1, with the record playing unit, the doors of the radio unit and the louvres of the speaker unit all in closed position.

I claim:

The ornamental design for a combination radio and phonograph table, as shown.

HERBERT L. WEISBURGH.
